UNITED STATES PATENT OFFICE.

ERNST E. ENGLUND, OF MOLINE, ILLINOIS, ASSIGNOR TO D. M. SECHLER IMPLEMENT & CARRIAGE COMPANY, OF MOLINE, ILLINOIS, A CORPORATION OF ILLINOIS.

PLANTER.

1,313,475.

Specification of Letters Patent.

Patented Aug. 19, 1919.

Application filed July 6, 1918. Serial No. 243,571.

To all whom it may concern:

Be it known that I, ERNST E. ENGLUND, a citizen of the United States, and a resident of Moline, in the county of Rock Island, 5 State of Illinois, have invented certain new and useful Improvements in Planters, of which the following is a specification, reference being had to the accompanying drawings.

10 This invention relates to improvements in seed-planters of the type wherein the dropping mechanism is positively actuated by means of pitmen connected to the axle of the supporting wheel. As heretofore constructed it has been deemed necessary to arrange such pitmen outside of the main frame. Such construction has been objectionable owing to the liability of damage to the pitmen by striking stumps, stones and other obstructions. It is one of the objects 15 of this invention to provide a more compact and a stronger construction whereby the said pitmen will be more effectually protected against damage at all times. It is a further 20 object of the invention to provide an improved crank-shaft for connection to the forward ends of the pitmen which shall always insure the pitmen being correctly connected therewith; which will insure proper lubrication of the bearings for the shaft for a long period of time, and which can be readily and economically manufactured. These 25 objects I attain by the construction and arrangement of parts shown in the drawings and hereinafter particularly described. That which I believe to be new will be set forth in the claims.

In the drawings:

Figure 1 is a side elevation of a one-row 30 drill embodying my improvements, a portion of one of the side bars of the main frame being broken away, as is also a portion of the bottom of the seed-hopper;

Fig. 2 is a plan view of the machine shown 35 in Fig. 1, with the seed-hopper removed and a portion of the rim of the supporting wheel broken away;

Fig. 3 is a longitudinal central section 40 through my improved crank-shaft, the bearings for the same also being shown in section;

Fig. 4 is a perspective view of the crank- 45 shaft shown in section in Fig. 4, but with

the bevel gear member shown in Fig. 3 removed; and

Fig. 5 is a face view of the bevel gear member of the crank-shaft.

Referring to the several figures of the drawing where corresponding parts are indicated by like reference numerals, 10 indicates the main frame of the machine, the side bars of which are connected together at their rear ends by a rod 11. 13 indicates a heavy cast bracket bolted between and connecting the two side bars of the frame near the forward end thereof. Projecting forwardly from this bracket 13 are ears through which passes a rod 14 that serves as a pivot upon which an ordinary seed-hopper is mounted, as usual. Such seed-hopper is indicated by 15, and has rotatably mounted in its bottom the usual seed-delivering plates, such plates being rotated by the driving of a gear ring 16, as usual. The heavy bracket 13 has rearwardly-extending arms 17 as shown in Fig. 2, which provide suitable bearings for a crank-shaft, to be described more in detail hereinafter. The removable upper half of the bearings referred to are indicated by 18. 19 indicates the usual supporting and covering wheel, located between the side bars of the frame 10, and mounted on an axle 19 whose ends are journaled in the side bars of the frame. 20 indicates a runner whose curved upper end is bolted to one face of a draft plate 21 that is riveted between the front ends of the side bars of the frame 10. The rear end of the runner or shoe is bifurcated, as usual, to receive the lower end of a seed-spout 22, said spout being held in position by a pair of braces 12, that are connected at their upper ends to the side bars of the frame.

23-24 indicate two pitmen that, at their rear ends, are journaled, respectively, on cranks 25-26 that are formed on the axle 19, such cranks being so disposed as to be a quarter turn or ninety degrees apart. The forward ends of these pitmen are connected to crank portions of a shaft 27. This shaft 100 comprises a hollow body portion, as best shown in Fig. 3, and at one end, and formed integral with the body portion, is a crank arm 28, terminating in a journal 29, upon which the forward end of the pitman 23 is 105 rotatably mounted. Formed upon the other

end of the body of the hollow shaft 27 is a short stud 30, the edge of which is for the most part concentric with the axis of the shaft, but which also has a flattened portion, 5 as at 31. Upon this stud 30 is mounted a bevel wheel 32, the hub thereof being provided with a central opening of a shape to correspond to the shape of the stud, and hence such gear or wheel is not only non- 10 rotatably mounted, but is always necessarily so placed that a journal carried by it, and preferably formed integral with it, will always stand in correct relation to the journal or pin 29 at the other end. The journal 15 or pin projecting from the bevel wheel 32 is indicated by 33. The bevel wheel is held in place by a bolt 34, the head of which fits in an angular socket, as shown in Fig. 3, in the end portion of the body of the shaft, 20 such bolt projecting through said end and through the gear, and being held in place by a nut 35, a washer 36 being preferably interposed between the nut and the face of the gear. To the journal or pin 33 the forward 25 end of the pitman 24 is suitably connected. 37 indicates openings through the wall of the body portion of the shaft, such openings being located adjacent to the ends of such body portion where they will be covered by 30 the bearings 17. Through these openings 37 lubricant contained within the hollow body will pass to keep the bearings properly lubricated. Such lubricant will preferably be of thick or heavy variety, and will be inserted 35 in place through an opening in that end of the body that carries the arm 28, which opening is normally closed by a screw-threaded plug 38, as shown. A pair of 40 handles will, of course, be properly secured to the frame of the machine so as to project rearwardly therefrom, as usual, but I have not deemed it necessary to show the same in connection with the machine illustrated.

45 With a machine having its parts constructed and arranged as shown and described, the pitmen are so located as to be much freer from liability to injury than in the constructions ordinarily employed, for 50 with the side bars of the main frame located in relation to the pitmen, as shown, they will, to a large extent, guard such pitmen from contact with obstructions that might damage them. Furthermore, by connecting 55 the rear ends of the pitmen to cranks that are located between the side bars of the frame and the hub of the supporting wheel, a construction is provided that is not only more compact, but very much stronger than 60 where the cranks are at the outer ends of the axle and where each crank is only supported from one end. Such improved arrangement of the pitmen also enables the machine to be provided with a shorter crank-shaft for 65 the forward ends of the pitmen, which also

contributes to greater strength. Such forward crank-shaft is very simply and cheaply made, as it comprises but two main parts, namely, the body portion, with which is cast the crank portions 28-29, and the gear 70 wheel portion 32, with which is cast the journal or pin 33, and by making the body portion of such shaft hollow, a sufficiently large quantity of suitable lubricant can be contained therein to insure the bearings being 75 kept properly lubricated for a comparatively long time.

What I claim as my invention and desire to secure by Letters Patent is:—

1. A shaft for rotating the seed-dropping mechanism of a planter of the class described, said shaft comprising a hollow body adapted to contain a lubricant and having openings through the body for the passage of such lubricant to the bearings of the shaft, 80 a crank formed on one end of said body, and a gear secured concentrically upon the other end of said body, and having a crank-pin 85 thereon in predetermined correct relation to the crank at the other end of the shaft. 90

2. A shaft for rotating the seed-dropping mechanism of a planter of the class described, said shaft comprising a hollow body adapted to contain a lubricant and having openings through the body for the passage of such lubricant to the bearings of the shaft, a crank formed on one end of said body, a gear secured concentrically upon the other end of said body and having a crank-pin projecting from its outer face, 100 and means for compelling engagement of said gear with said body only in a predetermined position for insuring the correct relative arrangement of its crank-pin with respect to the crank at the other end of the 105 shaft.

3. A shaft for rotating the seed-dropping mechanism of a planter of the class described, said shaft comprising a hollow body adapted to contain a lubricant and having openings through the body for the passage of such lubricant to the bearings of the shaft and also having an end opening for inserting the lubricant in the body, a closure for said last-named opening, said body having a crank on one of its ends and a stud on the opposite end, and a gear non-rotatably secured on said stud, the axes of the hollow body and the gear being coincident and the gear being provided with a crank arranged 110 in correct predetermined relation to the crank at the other end of the shaft. 115

4. A shaft for rotating the seed-dropping mechanism of a planter of the class described, said shaft comprising a hollow body 120 adapted to contain a lubricant and having openings through the body for the passage of such lubricant to the bearings of the shaft, said body having a crank formed on one of its ends and a stud on its other end, 125

- and a gear mounted on said stud and having a crank-pin on its outer face, said stud and the opening in the gear that receives the stud being formed to compel the gear to occupy a predetermined position so that the crank-pin thereon will stand in proper relative position with respect to the crank at the other end of the shaft, the axes of the hollow body and gear being coincident.
- 5 10 5. A shaft for rotating the seed-dropping mechanism of a planter of the class de-

scribed, said shaft comprising a hollow body having a crank formed on one of its ends and a stud on its other end, a gear non-rotatively mounted on said stud and having a 15 crank-pin on its outer face, and a bolt located in the hollow body and extending through the end thereof and through the stud and the gear for securing the gear against movement endwise of the stud.

ERNST E. ENGLUND.
